UNITED STATES PATENT OFFICE.

FRANK H. HALL, OF YONKERS, NEW YORK, ASSIGNOR TO STRAUSS MANUFACTURING COMPANY, OF NEW YORK, N. Y., A CORPORATION OF NEW JERSEY.

DESIGN FOR A STATUETTE.

42,624.

Specification for Design.

Patented June 18, 1912.

Application filed April 4, 1912. Serial No. 688,553. Term of patent 7 years.

To all whom it may concern:

Be it known that I, FRANK H. HALL, a citizen of the United States of America, residing at Yonkers, Westchester county, and State of New York, have invented a new, original, and ornamental Design for Statuettes, of which the following is a specification, reference being had to the accompanying drawing, forming part hereof, which represents a perspective view of a statuette, showing my new design.

I claim:

The ornamental design for a statuette as shown.

Signed at New York city, New York, this 3rd day of April, nineteen hundred and twelve (1912).

FRANK H. HALL.

Witnesses:

EDWARD A. JARVIS,
ESTELLE O. HAMBURGER.
